J. P. FRANK

BURETTE

Filed March 23, 1923

INVENTOR

John Peter Frank.

Patented Dec. 23, 1924.

UNITED STATES PATENT OFFICE.

JOHN PETER FRANK, OF PAPAIKOU, TERRITORY OF HAWAII.

BURETTE.

Application filed March 23, 1923. Serial No. 627,230.

To all whom it may concern:

Be it known that I, JOHN PETER FRANK, a citizen of the United States, residing at Papaikou, county of Hawaii, Territory of Hawaii, have invented new and original Improvements in Burettes, of which the following is a specification.

This invention relates to the design and manufacture of a burette which will permit all kinds of fluids and chemicals to be used in laboratories and manufacturing plants so that the said burettes will protect the fluids and chemicals contained therein free from any dust, oxidation or other contamination, and which may be drawn off through a stop-cock fitted in the lower end, and to permit the person using the same to measure the amount drawn off by means of units of measurement indicated upon the side of the burette.

In ordinary burettes now in use, difficulty is had in filling, rendering it necessary to use a detached funnel. Also with such burettes it is necessary to remove detached funnel from top of burette and replace same with a cork as a means of keeping the solution in the burette free from dust, when not in use. As the cork or stopper must be again removed when the solution is drawn off, from the bottom of burette, considerable contamination of chemicals with foreign matter ensues, and oxidation of chemical solutions takes place when using this ordinary burette.

To overcome these objections and defects, I have therefore invented and designed a burette as shown in the single figure of the drawing, which is a side elevation, so that the same shall contain an integral funnel bowl A at the top, which bowl will be an extension of the hollow shaft A of the burette, enlarged so as to form a semi-globular or funnel-shaped opening, rendering it unnecessary to use a detached funnel for filling. Immediately below the attached funnel there is a principal stop-cock C, provided with a central vertical passage c for the admission of fluids and chemicals to the hollow shaft B, and an inclined vertically disposed passage c', for the escape of air during filling of the burette, the passages c and c' being in the same longitudinal plane. Below the stop-cock C is the hollow shaft B, cylindrical in shape, and adapted for holding a fluid or chemical. At the lower end of the hollow

cylinder B is located a second stop-cock D which contains one transverse passage d for draining off the fluid or chemical, said stop-cock being made of the same material as the complete burette. Both the upper and lower stop-cocks are of the familiar design permitting the same to be turned with a handle at the side and removed for the purpose of cleaning. The upper stop-cock may be entirely removed, and, when so removed, a brush or other mechanical cleansing utensil can be inserted directly into the burette so as to come in contact with the inside walls of the cylinder, and thus facilitate cleansing.

I claim:

1. In a burette, in combination, a hollow shaft portion having graduations thereon, a funnel at the upper end thereof and having a vertical passage registering with the bore of the said shaft, a stop-cock having a transverse passage adapted to connect the passage between the funnel and the bore of the shaft, said stop-cock also provided with a second passage operably connected with the said bore and leading outside the container above the stop-cock to permit escape of air from the shaft when filling, and to prevent entrance of extraneous matter to said shaft when the aforesaid stop-cock is in passive position, said stop-cock passages adapted to be simultaneously opened and closed, and means for discharging the contents of said shaft at its lower end.

2. In a burette, in combination, a container comprising a hollow shaft portion having graduations thereon, an integral filling funnel at the upper end of said hollow shaft and having a passageway registering with the bore of said shaft, a turning plug mounted in said shaft below the said funnel, said turning plug having a transverse vertical passage therethrough in register with the bore of the shaft and the outlet passage of the funnel, when the device is in filling position, said turning plug also being provided with a second transverse passage therethrough disposed obliquely to the vertical passage and adapted to communicate with the bore of the hollow shaft, and provide an air escape when said turning plug is in filling position, said second passage leading outside the container above the turning plug, the outlet end of the ver-

tical passage and the inlet end of the oblique passage lying within the area of the bore of the hollow shaft, when in filling position, the discharge end of said oblique passage adapted to be blanked when the turning plug is in passive position, whereby to prevent entrance of extraneous material to the bore of the hollow shaft, both of said transverse passages adapted for simultaneous opening and closing and a ¹⁰ discharge stop-cock in the lower portion of said shaft.

JOHN PETER FRANK.
